PLIER TYPE TOOL FOR TRACKLESS
TROLLEY WIRE

Thomas F. Fleming, Dorchester, Mass.

Application September 18, 1951, Serial No. 247,028

5 Claims. (Cl. 81—5.1)

1

This invention relates to a tool for the handling of trackless trolley wire.

Trackless trolley wire is a metallic cable utilized for the supplying of electric energy to a trolley car and is customarily supported above street level by means of support posts, support cables and clamps. The wire itself is of a substantially circular cross-section segmentally grooved out on opposing sides of the vertical center line of the wire at points above the geometric center. Thus the cross-section of the wire appears to be formed of a small upper annular section superposed on a somewhat larger and lower annular section, the adjacent sides of which sections define substantially V shaped opposing grooves.

A short section of the wire is relatively stiff and will readily withstand the thrust of the conductor extending from the trolley car to the wire. However in long lengths the wire tends to coil and twist rendering the handling thereof exceedingly difficult. Thus in the installation of clamp ears, splice ears, and assembly tips the tendency of the wire to twist and coil presents a serious problem.

It is a primary object of this invention to provide a tool which will facilitate the handling of trackless trolley wire.

It is an important object of this invention to provide a tool which will facilitate the installation of clamp ears, splice ears and assembly tips on trackless trolley wire.

It is a principal object of this invention to provide a tool which will improve safety conditions in the handling and installation of trackless trolley wire.

It is another object of this invention to provide a tool which may be employed to hold a section of trackless trolley wire in a desired position.

It is yet another object of this invention to provide a tool which may be employed to twist a section of trackless trolley wire into a desired position.

These and other allied objectives of the invention are attained by providing a tool having opposed die parts, which dies have opposed lip portions for engaging in the grooves of the trackless trolley wire, and each of which dies is internally grooved adjacent a lip portion for receipt of a portion of the circumference of the wire. To insure of secure engagement with the wire the dies also have grooved wing portions laterally extending from the body of the twister tool.

The invention will be more fully understood by reference to the following detailed description and appended drawings wherein:

2

Figure 1 is a view of the tool in perspective;

Figure 2 is an enlarged view of a portion of the tool of Figure 1;

Figure 3 is a plan view of the portion of the tool shown in Figure 2;

Figure 4 is a perspective view of the portion of the tool shown in Figures 2 and 3;

Figure 5 is a sectional view illustrating the manner in which the dies engage the wire; and

Figure 6 is a perspective view illustrating a portion of a wire installation and the manner in which the tool engages the wire.

Referring to Figures 1, 2, 3 and 4 particularly, there is indicated generally a tool having a body portion 2 comprised of crossed arms 3 and 4 secured together and pivoted at 5 between handle ends 6 and 6' and jaw ends 7 and 8. Positioned between pivot 5 and jaw end 8 there is secured in arm 3 a die or insert 9 having a groove 10 and a lip 11. Wing portions 12 and 13 extend transversely of body portion 2 and are provided with extensions of groove 10, the said groove thus passing completely through the die transversely thereof.

Secured in arm 4 in opposed relation to die 9 is a second die 14 having a groove 15, a lip 16 and wing portions which are counterparts of the same elements in die 9.

Jaw ends 7 and 8 are each provided with splined portions 19 and 20.

Referring to Figure 5 there is shown in enlarged section dies 9 and 14 engaging therebetween trolley wire 21, the lower portion 22 of the wire being fixedly seated in the chamber defined by grooves 10 and 15, and grooves 23 and 24 of the wire being securely engaged by lip portions 11 and 16.

As shown most clearly in this Figure 5, the dies as viewed in end section have internal smooth faced concave grooves and from each groove the lip or lip portions 11 and 16 extend at an obtuse angle with respect to the groove face to insure of a secure positive engagement with the trolley wire.

In Figure 6 trolley wire 21 is shown engaged by the tool 1 which holds the wire 21 in a predetermined position as for the securing of clamp 32 to the wire. Clamp 32 in this typical installation is secured to insulator 31 which is in turn suspended from a support cable 30. The support cable may of course be suitably fastened about vertical supports (not shown).

The tool of invention, in operation, is extended in opened position towards the wire to be manipulated and wire 21 passes between jaw ends 7

and 8 and is guided into the chamber formed by grooves 10 and 15 by partially closing the tool as the wire 21 enters, the lips 11 and 16 passing over the circumferential portion of the wire 21 to engage in the grooved portions of the wire.

With the tool fully closed, the wire portion 22 is firmly seated in the chamber defined by grooves 10 and 15 and the upper portion of the wire 21 is positioned in spacing defined by the arms 3 and 4 and the upper surfaces of the dies as shown in Figure 6. The wire then may be readily twisted into any desired position, the firm grasp afforded by the laterally extending wing portions serving to facilitate the twisting operation.

Thus the wire 21 may be readily handled with the tool of invention as the wire is being unreeled, the tool serving to retain the wire straight and without twist. The tool serves a particularly useful function in retaining the wire in position during stringing. As illustrated in Figure 6 the tool is effective to position the wire for the mounting of support clamps; the tool may be similarly used when installing assembly tips and finds particular utility when the grooved wire is connected with splice ears where the twister tool is used to move the splice ears to proper position on the grooved trackless trolley wire.

It will be understood that this invention is susceptible to modification in order to adopt it to different usages and conditions and accordingly, it is desired to comprehend such modifications within this invention as may fall within the scope of the appended claims.

I claim:

1. A tool for the holding and twisting of trackless trolley wire comprising a body portion including handle means, and a pair of relatively movable opposed dies secured in said body portion in spaced relation with said handle means, said dies as viewed in end section having opposed lips and each die having an internal smooth faced concave groove from which a said lip extends at an obtuse angle with respect to the groove face for the receipt of a portion of the circumference of said trolley wire.

2. A twister tool for the holding and twisting of trackless trolley wire comprising a body portion including crossed arms pivoted between opposing ends thereof, one said end having handle means and the other said end having opposed dies secured in the said arms, said dies as viewed in end section having opposed lips and each die having an internal smooth faced concave groove from which a said lip extends at an obtuse angle with respect to the groove face for the receipt of a portion of the circumference of said trolley wire.

3. A twister tool for the holding and twisting of trackless trolley wire comprising a body portion including crossed arms pivoted between opposing ends thereof, one said end having handle means and the other said end having relatively movable opposed dies secured in the said arms, said dies having wing portions provided with opposing smooth faced concave grooves extending through the dies and also having opposed lips each of which intersects with and extends at an obtuse

angle from each said groove and lies adjacent one edge of each of the grooves and co-extensive therewith, said grooves in the closed position of said tool defining a substantially closed chamber for the receipt of a portion of the circumference of said trolley wire.

4. A tool for the holding and twisting of trackless trolley wire having longitudinal grooves therein comprising a longitudinally extending body portion including crossed arms pivoted between opposing ends thereof, one said end having handle means and the other said end having dies secured in opposed relation, one die in each of the arms, each said die comprising wing portions extending transversely of said body portion on either side thereof and each being provided with a smooth faced concave groove extending transversely through the die, said grooves being positioned in opposed relation to define in the closed position of the arms a chamber conforming to the configuration of a portion of the circumference of the said trolley wire, said dies also having adjacent an edge of each said groove and co-extensive therewith a lip which intersects with and extends at an obtuse angle with respect to a groove face, the lips of the said dies in closed position of the arms being adapted to engage said wire therebetween by engagement with the grooves of said wire.

5. A tool for the holding and twisting of trackless trolley wire having longitudinal grooves therein comprising a longitudinally extending body portion including crossed arms pivoted between opposing ends thereof, one said end having handle means and the other said end having dies secured in opposed relation, one die in each of the arms, each said die comprising wing portions extending transversely of said body portion on either side thereof and each being provided with a smooth faced concave groove extending transversely through the die, said grooves being positioned in opposed relation to define in the closed position of the arms a chamber conforming to the configuration of a portion of the circumference of the said trolley wire, said dies also having adjacent an edge of each said groove and co-extensive therewith a lip which intersects with and extends at an obtuse angle with respect to a groove face, the lips of the said dies in the closed position of the arms being adapted to engage said wire therebetween by engagement with the grooves of said wire, and said dies and adjacent arm ends defining an internal spacing for the enclosing of the remainder of the circumference of said wire.
